(57) **CLAIM**

The ornamental design for a bridge for a dual-port throttle body, as shown and described.

DESCRIPTION

FIG. 1 is a perspective view of a bridge for a dual-port throttle body showing my new design.

FIG. 2 is a top plan view thereof, the bottom being flat and devoid of surface ornamentation.

FIG. 3 is a cross-sectional view taken along line 3-3 of FIG. 2 showing a left side view thereof; and,

FIG. 4 is a cross-sectional view thereof taken along line 4-4 of FIG. 2 showing a right side view thereof.

Background features are shown in broken lines for illustrative purposes only and form no part of the claimed design.
